UNITED STATES PATENT OFFICE.

WILLIAM N. SHARP, OF CHICAGO, ILLINOIS.

TOILET ARTICLE.

1,132,126.

Specification of Letters Patent. Patented Mar. 16, 1915.

Application filed September 3, 1914. Serial No. 860,084.

To all whom it may concern:

Be it known that I, WILLIAM N. SHARP, a citizen of the United States, residing at Chicago, in the county of Cook and State of Illinois, have invented a new and useful Improvement in Toilet Articles, of which the following is a specification.

My invention relates to an improved construction of a combined comb and brush, which shall render the article compact for convenience in carrying it, and thereby adapt it particularly for travelers' use, and permit the comb and brush each to be readily unfolded for desired successive use, from 15 and as readily folded into a handle-forming case to which they are hinged.

In the accompanying drawing, Figure 1 shows my improved article by a perspective view with the brush wholly and the 20 comb partly turned on their respective hinges out of their handle-forming receiving case; Fig. 2 is a longitudinal vertical section through the case, showing in folded position therein the brush in elevation and the comb in section; Fig. 3 is a section through the case on the irregular line 3, Fig. 25 2, omitting the brush and showing the comb broken and unfolded, and Fig. 4 is a section on line 4, Fig. 2.

The case 5, shown of oblong rectangular form, is made of any suitable material, though preferably of sheet metal and best, for the sake of lightness, durability and 30 cleanliness, of aluminum. It comprises a bottom-face 6, a closed end 7 shown slightly recessed on its upper edge, an open end containing a hinge-pintle 8, and parallel sides 35 9 and 10. The case is open along its top face. The side 10 contains a longitudinal slot 11 terminating short of the open case-end and extending to some depth, at 12, laterally into the edge of the adjacent end 7; and a curved recess 13 is provided in the 40 edge of the base near the forward end of the slot. A hair-brush 14, the back of which is also preferably of aluminum, carries on one end a hinge-knuckle 8^a for hingedly connecting with the pintle 8 the brush to adapt the latter to be folded, when out of use, into 45 the case, which it fits, as shown in Figs. 2 and 4, and unfolded to extend into the posi-

tion of its use represented in Fig. 1, wherein the case affords a handle by which to manipulate it. A comb 15, which it is also desirable to form of aluminum, is pivotally 55 fastened, at one corner, to the corner of the base 6 near the slot at 12, to adapt it to fold hingedly through the slot 11 into the case, which it fits, as shown in Figs. 2 and 4, and to be unfolded to the position represented in Fig. 3 for extending it from the case for use, employing the case as a handle. The comb should be provided with a notch indicated at 15^b, in the face of its back 15^a at a point in the latter that comes coincident with the recess 13 when the comb is folded into place to admit the thumb-nail of the user and thus afford convenient access to the comb for unfolding it. The brush is accessible in the same way, for unfolding it, at a notch 14^a in its outer end 70 through the recessed upper edge of the case-end 7.

As will be seen, the brush and comb fold and unfold in directions at right-angles to each other, and when they are folded together in the case the comb lies or extends along and out of contact with the bristles of the brush, being held out of contact by the engagement of the knuckle 8^a with the bottom face 6.

By the construction thus shown and described, the several articles are not only inseparably attached together, thus preventing either the brush or the comb from being 85 mislaid or lost by separation for use from the case-forming handle, but the device is neat and sanitary, besides being compact and thus extremely convenient to be carried, particularly by travelers, and especially 90 those traveling in automobiles to points of alighting for refreshment without staying or intending to stay there over night and where they find it desirable to use these 95 toilet-articles in restoring presentable appearance at table.

What I claim as new and desire to secure by Letters Patent is—

A toilet-article comprising an oblong rectangular case open along one face, closed at 100 one end and having a longitudinal slot in one side near the opposite face and extend-

ing through said closed end, a brush hinged in the opposite open end of the case to fold and fit lengthwise into it clear of the bottom to leave a space, and a comb pivoted at one end to the bottom face of the case near its opposite end to fold into the latter through said slot at a right-angle to the direction of

folding the brush and extend into said space and along and out of contact with the brush-bristles.

WILLIAM N. SHARP.
